UNITED STATES PATENT OFFICE

100,540

DESIGN FOR A CHAIR

William G. Carlson, Gardner, Mass.

Application June 17, 1936, Serial No. 63,348

Term of patent 7 years

To all whom it may concern:

Be it known that I, William G. Carlson, a citizen of the United States, residing in Gardner, in the county of Worcester and State of Massachusetts, have invented a new, original, and ornamental Design for a Chair, of which the following is a specification, reference being had to the accompanying drawing, forming part thereof.

Fig. 1 is a front perspective view of the chair, showing my new design,

Fig. 2 is a front view,
Fig. 3 is a rear perspective view,
Fig. 4 is a side elevation, and
Fig. 5 is a top plan view thereof.
I claim:
The ornamental design for a chair, as shown.

WILLIAM G. CARLSON.
